US0D1003425S

(12) United States Design Patent (10) Patent No.: US D1,003,425 S
(45) Date of Patent:  *Oct. 31, 2023

(54) VAPORIZER DEVICE

(71) Applicant: Dr. Dabber Inc., Las Vegas, NV (US)

(72) Inventors: Jamie Michael Rosen, Las Vegas, NV (US); Pantelis Costas Ataliotis, Las Vegas, NV (US)

(73) Assignee: Dr. Dabber Inc., Las Vegas, NV (US)

(*) Notice: This patent is subject to a terminal disclaimer.

() Term: 15 Years

(21) Appl. No.: 29/643,605

(22) Filed: Apr. 10, 2018

(51) LOC (14) Cl. 27-02

(52) U.S. Cl.

USPC D27/162; D27/100

(57) CLAIM

We claim the ornamental design for a vaporizer device, as shown and described.

DESCRIPTION

FIG. 1 is a perspective view of a vaporizer device;

FIG. 2 is a left-side view thereof;

FIG. 3 is a right-side view thereof;

FIG. 4 is a top view thereof;

FIG. 5 is a bottom view thereof;

FIG. 6 is a front view thereof; and,

FIG. 7 is a back view thereof.

The broken lines shown throughout the FIGURES depict unclaimed subject matter and form no part of the claimed design.

1 Claim, 6 Drawing Sheets
